ELECTROMETER VACUUM TUBE

Auguste Louis Marie Antoine Rouy, New York,
N. Y., assignor to L. L. H. Company, Erie, Pa.,
a partnership comprising Hugh C. Lord,
Thomas Lord, and Blanche M. Hartman

Application December 22, 1944, Serial No. 569,403

6 Claims. (Cl. 250—27.5)

1

My invention relates broadly to electrometer vacuum tubes and more particularly to an improved construction of highly sensitive electrometer vacuum tube.

This application is a continuation-in-part of my application Serial No. 552,892 filed September 6, 1944, for Electrometer vacuum tube.

One of the objects of my invention is to provide an improved construction of electrometer vacuum tube having means for increasing the sensitivity of the electrometer tube.

Another object of my invention is to provide a construction of electrometer vacuum tube containing control grid, cathode and anode electrodes containing means for effecting mutual cancellation of electron and ion charges upon the surface of a shield surrounding the control grid.

Still another object of my invention is to provide an improved construction of electrometer vacuum tube containing a control grid, a cathode system and an anode electrode with a shield of dielectric material interposed between the control grid and the cathode system for preventing electrons from the cathode system from bombarding the control grid.

Still another object of my invention is to provide a construction of electrometer vacuum tube including a control grid, a cathode system and an anode electrode with a shield of dielectric material interposed between the control grid and cathode system for preventing any positive ions which are liberated by electrical bombardment of the anode from reaching the control grid.

Still another object of my invention is to provide a construction of quartz or glass shield for the control grid of an electrometer vacuum tube, including a control grid, cathode system and anode, which allows acceleration of electrons from the cathode system toward the anode through the field created by voltage applied to the grid while obstructing the flow of electrons from the cathode system to the grid and preventing the attachment upon the grid of ions liberated by the electron bombardment of the anode.

Other and further objects of my invention reside in the improved construction of electrometer vacuum tube as set forth more fully in the specification hereinafter following by reference to the accompanying drawings in which:

Figure 1 is a vertical sectional view taken through the electrometer vacuum tube of my invention showing the quartz or glass shield enclosing the control grid; Fig. 2 is a transverse sectional view taken on line 2—2 of Fig. 1; Fig. 3

2

is a transverse sectional view taken on line 3—3 of Fig. 1; and Fig. 4 is a theoretical view illustrating the effect of the shield in the electrometer vacuum tube of my invention in effecting mutual cancellation of electron and ion charges upon the surface of the shield in the electrometer vacuum tube.

In my co-pending application 552,892, supra, I have explained the functions of an electrometer vacuum tube in the measurement of very small currents or voltages where the total amount of energy is extremely low such as, for instance, in the case of voltages produced by pressure on a piezo electric quartz crystal cell. I have pointed out that it is of the utmost importance to avoid any losses of the minute charge delivered to the control grid of the electrometer vacuum tube. I have discovered that the sensitivity of the electrometer vacuum tube of my invention as set forth in application 552,892, supra, may be substantially increased by protecting the control grid of the electrometer tube against any bombardment by electrons released from the cathode system or against the attachment of any positive ions liberated by the electronic bombardment of the anode. To effect cancellation of such electrons and ion charges with respect to the control grid, I provide a cylinder of quartz or glass spaced with respect to the control grid and arranged to enclose the control grid for obstructing the control grid against any bombardment by electrons emanating from the cathode system and at the same time preventing the attachment to the control grid of any positive ions which are liberated by the electronic bombardment of the anode. The positive ions and the electrons carrying a negative charge of electricity fall upon the outer surface of the glass or quartz tube and their average electrical charges cancel each other on the surface of the glass or quartz tube. However, the acceleration of electrons from the cathode system toward the anode through the field created by the voltage applied to the control grid is not affected by the presence of the glass or quartz screen. The grid current of the electrometer tube is thus maintained absolutely negligible regardless of the voltage applied to the control grid for thus increasing the sensitivity of the electrometer vacuum tube for operation under control of the voltages applied to the control grid.

Referring to the drawings in detail the electrometer vacuum tube is represented as enclosed by an envelope 1 which may be formed in two parts having relatively wide flanges 2 and 3 abutting face to face and serving as supports for the

radially projecting rod members 4, 5 and 6 which provide mounting means for cylindrical anode electrode 7 and which also forms supports for the radially extending rod members 8, 9 and 10 which extend from the ring member 11 which is disposed concentrically within the envelope of the tube and spacially related to the plate 7.

The ring member 11 provides supports for radially extending spring members 14, 15 and 16. Spring members 14, 15 and 16 are welded to the ring member 11 and project radially inwardly and serve as cantilever supports for the upper ends of filaments 17, 18 and 19 constituting the cathode system. The lower ends of the filaments 17, 18 and 19 are supported by the tripod member 20 which projects through the end of the envelope of the electrometer vacuum tube and terminates at 21 forming an electrical connection for the cathode system. The opposite electrical connection for the cathode system is made to radially extending member 8 or any other of the supporting rods that connect to the ring member 11. Thus the cathode system is maintained taut under the action of the spring arms 14, 15 and 16 as the filaments are heated.

The control grid for the electrometer vacuum tube is represented at 22 entering the envelope of the electrometer vacuum tube through the end as represented at 23 and extending axially of the tube and centrally with respect to the cathode system formed by filaments 17, 18 and 19 and cylindrical anode 7.

The shield of my invention consists of a glass or quartz tube 24 which incloses the control grid 22 and extends thereover in spaced relation with respect thereto. The glass or quartz tube 24 has one end thereof flanged as represented at 25 within which ring member 26 is embedded. Ring member 26 serves as a mechanical support for the relatively fragile glass or quartz tube 24. The ring member 26 is supported with respect to ring member 11 through arm 27 which extends radially to ring 11 introducing sufficient flexibility into the support to prevent shattering of the quartz or the glass tube 24 under condition of shock vibration. The ring member 26 is normally supported out of the plane of ring member 11 allowing sufficient displacement between the end 22a of grid 22 and the closed end 24a of tube 24 to prevent breakage of the shield 24 under condition of vibration.

As illustrated in Fig. 4 the electrons emanating from the filaments of the cathode system shown at 17, 18 and 19 are collected by anode 7 but are prevented from bombarding control grid 22 by the interposition of the dielectric shield 24. I have represented a path of electrons from filament 19 at 28, for example, being deflected at 29 by shield 24 and directed toward the anode 7 at 30. Ions liberated by bombardment of the anode 7 may take a path, for example, as represented at 31, but because of the interposition of dielectric surface 24 the ions are prevented from reaching control grid 22. Mutual cancellation of electrons and ion charges upon the surface of shield 24 is effected, thus preventing increase in grid current. The grid current is maintained absolutely negligible regardless of the voltage applied to the grid and the sensitivity and efficiency of the electrometer tube increased.

While I have described my invention in one of its preferred embodiments I realize that modifications may be made and I desire that it be understood that no limitations upon my inven-

tion are intended except as may be imposed by the scope of the appended claims.

What I claim and desire to secure by Letters Patent of the United States is as follows:

1. An electrometer tube comprising an envelope enclosing a control grid, a cathode system, and an anode, a shield of dielectric material surrounding said control grid and interposed between said control grid and said cathode system and means resiliently suspending said shield within said envelope in spacial relation to the control grid interiorly of said shield and in spacial relation to said cathode system exteriorly of said shield.

2. An electrometer tube comprising an envelope enclosing a control grid, a cathode system, and an anode, a quartz shield surrounding said control grid and interposed between said control grid and said cathode system and means resiliently suspending said shield within said envelope in spacial relation to the control grid interiorly of said shield and in spacial relation to said cathode system exteriorly of said shield.

3. An electrometer tube comprising an envelope enclosing a control grid, a cathode system, and an anode, supporting means for said cathode system within said envelope, a tube of dielectric material surrounding said control grid and spacially related thereto and disposed between said cathode system and said control grid, and means connected with said supporting means and resiliently suspending said tube of dielectric material for movement under conditions of shock vibration without abutment with said control grid or said cathode system.

4. An electrometer tube comprising an envelope enclosing a control grid, a cathode system, and an anode, a tubular member of dielectric material surrounding said control grid and interposed in spacial relation between said control grid and said cathode system for shielding said control grid against bombardment of electrons from said cathode system and from ions liberated by electronic bombardment of said anode, and means supporting said tubular member for axial or transverse movement with respect to said control grid.

5. An electron discharge device comprising an enclosing vessel, a grid electrode supported axially within said vessel, a cylindrical anode electrode surrounding said grid electrode, a ring-like member concentrically disposed with respect to said grid electrode and spaced from both said grid and anode electrodes, a multiplicity of filament electrodes supported by said ring-like member and extending in equidistant positions between said grid and anode electrodes, means supporting said ring-like member and said anode electrode for minimizing displacement of said electrodes under conditions of vibration whereby such displacement of said electrodes which may occur takes place in the same direction, a dielectric shield surrounding said grid electrode and interposed between said grid electrode and said filament electrodes, said dielectric shield being spacially related with respect to both said grid electrode and said filament electrodes and means extending from said ring-like member supporting said dielectric shield subject to displacement under conditions of vibration without abutment with either said grid or filament electrodes.

6. An electron discharge device comprising an enclosing vessel, a grid electrode supported axially within said vessel, a cylindrical anode electrode surrounding said grid electrode, a ring-like member concentrically disposed with respect to said anode electrode and disposed in spaced relation

with respect to one end of said anode electrode, resilient supports extending radially inward from said ring-like member to equidistant positions intermediate said grid and anode electrodes, filament electrodes carried by said resilient supports, means supporting said ring-like member and said anode electrode through the walls of said enclosing vessel for minimizing relative displacement of said filament and anode electrodes under conditions of vibration, and a tubular member of dielectric material surrounding said grid electrode and disposed in spacial relation with respect to said grid electrode and said filament electrodes and supported at one end thereof from said ring-like member whereby said tubular member of dielectric material is displaceable longitudinally and transversely under condition of vibration without abutting with either said grid or filament electrodes.
